Thomas E. Sturdevant, Denver, Colo.

Application July 16, 1934, Serial No. 52,598

Term of patent 3½ years

To all whom it may concern:

Be it known that I, Thomas E. Sturdevant, a citizen of the United States, residing at Denver, in the county of Denver and State of Colorado, have invented a new, original, and ornamental Design for a Contract Blank, of which the following is a specification.

Reference is made to the accompanying drawing which forms part of the specification.

I claim.

The ornamental design for a contract blank, as shown.

THOMAS E. STURDEVANT.
